UNITED STATES PATENT OFFICE.

EDWARD F. STEINMAN, OF CINCINNATI, OHIO.

HEADLIGHT-LENS.

1,252,505.

Specification of Letters Patent. Patented Jan. 8, 1918.

Application filed May 1, 1917. Serial No. 165,775.

To all whom it may concern:

Be it known that I, EDWARD F. STEINMAN, residing at Cincinnati, Hamilton county, State of Ohio, have invented certain new and useful Improvements in Headlight-Lenses, of which the following is a clear, full, and exact description, attention being called to the drawing which accompanies this application and forms a part thereof.

10 This invention concerns lenses for headlights and more particularly lenses which are used in connection with headlights for automobiles.

The object is to construct such a lens in a manner to do away with the objectionable glare thereby rendering the use of dimmers or other means for this purpose unnecessary.

The invention consists of the construction whereby this object is obtained and as described in the following specification and pointed out in the claim at the end thereof.

The construction is also illustrated in the accompanying drawing in which:

Figure 1. shows an axial section of a headlight embodying my invention.

Fig. 2. shows the inner side of a part of the lens used in connection therewith and embodying the features of my invention.

Fig. 3. is a cross-section of a lens of modified form.

In the drawing, letter A indicates the reflector provided with a suitable light which is not shown.

Letter B indicates the lens positioned at the open end of this reflector and held in place at the annular edge thereof by any suitable means.

It is made of glass by any of the approved methods of manufacture and may be cast, pressed or blown.

40 In profile it may be flat as shown in Fig. 3, or it may be convex or concave or of a combination of shapes as shown in Fig. 1.

In particular this shape comprises the conical center portion 5 and an annular zonal portion 6 around it and extending to the edge of the reflector.

45 The particular dimming effect whereby the glare is subdued is obtained by a number of concentric annular prisms C which are provided on the inner side of the lens on its side next to the light source. Each one of

these prisms is substantially triangular in cross-section in its protrusion from the body of the lens, and so presented toward the light source that both of its protruding surfaces

are impinged by the light waves; and so

that the light waves impinging on the radially inward side of the prism will be refracted in their passage through the lens

and thence to the outer air in a divergent direction, while the light rays converging

on the radially outward side of each prism will be so refracted that they will be convergent on their emergence from the lens

into the outer air. I am thus enabled to

secure divergent and convergent rays and to

treat each in a different manner, if desirable.

I prefer to treat the radially outward sides

so as to reduce the intensity of the con-

verging rays and to leave the other sides of

the prisms fully transparent, so that the diverging rays are not reduced in intensity.

This is especially desirable where the lens is used in a vehicle lamp since about one-half

of the light will be concentrated in the im-

mediate path of the vehicle, but so dimin-

ished in intensity as not to produce glare in

the eyes approaching in the opposite direc-

tion, while the diverging rays light the sides

of the roadway and branching roadways,

and are not subdued because they are by the

refraction distributed over a large area, and,

furthermore, are not thrown into the eyes

of anybody in such proximity to the vehicle

as to make the glare dangerous even if it

should be present in these unsubdued di-

vergent rays.

It may be produced in the formation of

the lens while the same is cast or blown by

imparting a rough surface to the particular

side of the prisms or it may be done by

grinding or sand-blasting or by coating,

etching, staining or painting the particular

side of the prisms by means of a substance

suitable for the purpose.

These prisms may cover the entire surface

of the lens or may be omitted from the cen-

tral portion thereof as shown in the draw-

ing.

Having described my invention I claim

as new:

A headlight lens comprising a series of

concentric annular prisms each of substan-

tially triangular cross section in its protrusion from the body of the lens, the inner inclined side of each of said annular prisms being arranged to diffuse away from the 5 axis of the lens incident rays and the outer inclined side of each of said annular prisms being arranged to refract incident rays sub-

stantially parallel with the axis of said lens, said outer inclined faces being treated to render them translucent.

In testimony whereof I hereunto affix my signature.

EDWARD F. STEINMAN.
